WAVEGUIDE MODE TRANSFORMERS

Eric Arthur North Whitehead, St. Albans, and John Alexander Christie Kinnear, Bromley, England, assignors to Elliott Brothers (London) Limited, London, England, a company of Great Britain

Application May 10, 1954, Serial No. 428,568

Claims priority, application Great Britain May 15, 1953

4 Claims. (Cl. 333—21)

This invention relates to improvements in waveguide mode transformers and is particularly concerned with the provision of waveguide mode transformers for transforming high-frequency electro-magnetic energy propagated in a rectangular section waveguide in the H_{10} mode into energy propagated in the H_{11} mode in a circular section waveguide.

It is an object of the present invention to provide a waveguide mode transformer of the general character referred to above which shall be capable of operation for precision purposes without undesirably large reflection of the incident energy and which shall be capable of reproduction on a commercial scale without the use of complicated fixtures and without the employment of a large skilled labour force.

According to one feature of the present invention a waveguide mode transformer for transforming energy propagated in the normal or H_{10} mode in a rectangular section waveguide into energy propagated in the H_{11} mode in a circular section waveguide comprises a transition section of a waveguide having a rectangular aperture at one end having dimensions corresponding to those of the rectangular section guide and a circular aperture at the other end having a diameter corresponding to that of the circular section waveguide, the two apertures having their edges contained in parallel planes and having their centre points located on the axis of the section, a passage extending towards the circular aperture from the rectangular aperture and of the same shape and cross-sectional area as the latter and another passage extending towards the rectangular aperture from the circular aperture and having its wall arranged to constitute part of the surface of a frustum of a cone having a larger end the diameter of which is substantially equal to that of the circular aperture and a smaller end of a diameter substantially equal to the smaller dimension of the rectangular aperture, the axes of the two passages being in alignment and the walls of the two passages meeting along curved lines.

In a modification of the waveguide mode transformer described in the preceding paragraph the transition section may be split longitudinally into two halves along the plane normal to the broad face of the rectangular passage and passing through the axis thereof, the two halves being displaced lengthwise relative to each other by a distance approximately equal to one quarter of the wave-length of the energy.

The invention also extends to a method of manufacturing a waveguide mode transformer according to either of the immediately preceding paragraphs, which comprises forming the said other passage, extending towards the rectangular aperture from the circular aperture, in a transition section of a waveguide having initially a passage therethrough of rectangular cross-section throughout its length, by removing part of the wall of the section by a machining or like operation.

In order that the invention may be more clearly un-

2

derstood two forms thereof will now be described by way of example with reference to the accompanying drawings in which:

Figure 1 is an elevation of the transition section of a waveguide taken from that end formed with the circular aperture;

Figure 2 is a section taken on the line II—II of Figure 1;

Figure 3 is a section taken on the line III—III of Figure 1, and

Figures 4 and 5 correspond to Figures 2 and 3 and show a modification.

In the example illustrated in Figures 1, 2 and 3 the waveguide mode transformer comprises a thick-walled transition section 1 of a waveguide having at one end a rectangular aperture 2 and at the other end a circular aperture 3.

A rectangular passage 4 of the same cross-sectional area and dimensions as the aperture 2 extends from the aperture 2 towards the circular aperture 3 and a passage 5 extends from the circular aperture 3 towards the rectangular aperture 2, the apertures 2 and 3 having their edges contained in parallel planes and having their centre points located on the axis of the section 1. The wall of the passage 5 constitutes part of the surface of a frustum of a cone (indicated in dotted lines in Figures 2 and 3), the diameter of the larger end of the frustum being substantially equal to that of the circular aperture 3 and the diameter of the smaller end thereof being substantially equal to the smaller dimension of the rectangular aperture 2. The walls of the passages 4 and 5 meet along curved lines indicated at 6 and 7 in Figures 2 and 3 respectively.

The transition section 1 described has a taper extending from the rectangular section passage 4 to the larger diameter end of the passage 5 which produces a rate of increase in the cross-sectional area of the passage 4, 5 through the section 1 which is least when the deviation from the rectangular passage 4 first takes place. This reduces considerably the fraction of energy reflected by the transition section.

The transition section 1 may be produced by cutting the passage 5 in a thick-walled waveguide section through which a rectangular passage corresponding to the passage 4 extends initially for the whole length thereof by cutting away part of the wall thereof by a machining or reaming operation.

Alternatively the transition section 1 may be produced by the electro-deposition of copper or other conducting metal on a suitably shaped mandrel.

In operation the section 1 is connected at the one end having the rectangular aperture to a waveguide having a correspondingly dimensioned rectangular passage therethrough and at the other end to a waveguide having a circular section passage therethrough corresponding in cross-sectional area to the aperture 3. High frequency electromagnetic energy propagated in the normal or H_{10} mode through the rectangular section guide is transformed by the transition section 1 into energy propagated in the H_{11} mode in the circular section guide and owing to the fact that the increase in cross-sectional area of the passage 4, 5 is least where the deviation from the rectangular passage 4 first takes place the fraction of energy reflected by the transition section is quite small.

The fraction of reflected energy may be considerably reduced by modifying the transition section 1 in the manner shown in Figures 3 and 4. In this modification, the transition section 1 of Figures 1, 2 and 3 is split along a plane normal to the broad face of the rectangular passage 4 and passing through the axis thereof into two halves 1a and 1b. The half 1a is seen in elevation in

Figure 3 as the section 4 occurs in the plane of the split. The two halves are displaced longitudinally relative to each other by a distance substantially equal to one quarter of the wavelength of the energy. The end faces of the two halves 1a and 1b forming the transition section are machined flat by cutting away the parts shown in broken lines.

The modified arrangement functions in the same way as that described with reference to Figures 1, 2 and 3 but has the additional advantage that any energy reflected from corresponding regions of the half sections 1a and 1b will be in anti-phase and will substantially nullify each other.

The wall of the passage 5 may form part of the surface of a volume of revolution which departs slightly from a straight-sided frustum of a cone in order to reduce further the fraction of energy reflected by the transition section. This may be achieved by suitably shaping the wall of the passage 5 where it intersects the passage 4, e. g. by forming the radius on the wall of the passage 5 at this location, so that the passages 5 and 6 blend smoothly into each other. The marginal surface of the passage 5 adjacent to the aperture 3 may also be curved or radious as will be understood.

What we claim is:

1. A waveguide mode transformer for transforming energy propagated in the normal or H_{10} mode in a rectangular section waveguide into energy propagated in the H_{11} mode in a circular section waveguide comprising a transition section of a waveguide having a rectangular aperture at one end having dimensions corresponding to those of the rectangular section guide and a circular aperture at the other end having a diameter corresponding to that of the circular section waveguide, the two apertures having their edges contained in parallel planes and having their centre points located on the axis of the section, a first passage extending towards the circular aperture from the rectangular aperture and of the same shape and cross-sectional area as the latter and a second passage extending towards the rectangular aperture from the circular aperture in axial alignment with said first passage and having its wall arranged to constitute part of the surface of a frustum of a cone having a larger end, the diameter of which is substantially equal to that of the circular aperture and a smaller end of a diameter substantially equal to the smaller dimension of the rectangular aperture, each wall of said first passage meeting the wall of said second passage along a curved line contained in the plane of said wall of said rectangular passage.

2. A waveguide mode transformer according to claim 1 wherein the transition section is split longitudinally into two halves along the plane normal to the broad face of the rectangular passage and passing through the axis thereof and the two halves are displaced lengthwise relative to each other by a distance approximately equal to one quarter of the wavelength of the energy.

3. A waveguide mode transformer for transforming energy propagated in the normal or H_{10} mode in a rectangular section waveguide into energy propagated in the H_{11} mode in a circular section waveguide comprising a transition section of a waveguide having a rectangular aperture at one end having dimensions corresponding to those of the rectangular section guide and a circular aperture at the other end having a diameter corresponding to that of the circular section waveguide, the two

65

4. Apertures having their edges contained in parallel planes and having their centre points located on the axis of the section, a passage extending towards the circular aperture from the rectangular aperture and of the same shape and cross-sectional area as the latter and another passage extending towards the rectangular aperture from the circular aperture and having that part of its wall lying to one side of a plane normal to the broader faces of the passage extending from the rectangular aperture and 5 containing the axis of the last-mentioned passage arranged to constitute part of the surface of a frustum of a cone and that part of its wall lying to the other side of said plane arranged to constitute part of the surface of a frustum of a similar cone displaced axially with respect to said first-mentioned frustum by a distance approximately equal to one quarter of the wavelength of the energy, each of said frustums having a larger end the diameter of which is substantially equal to that of the circular aperture and a smaller end of a diameter substantially equal to the smaller dimension of the rectangular aperture, the axes of said two passages being in alignment and the walls of the two passages meeting along the curved lines.

4. A waveguide mode transformer for transforming energy propagated in the normal or H_{10} mode in a rectangular section waveguide into energy propagated in the H_{11} mode in a circular section waveguide comprising a transition section of a waveguide having a rectangular aperture at one end having dimensions corresponding to those of the rectangular section guide and a circular aperture at the other end having a diameter corresponding to that of the circular waveguide, the two apertures having their edges contained in parallel planes and having their centre points located on the axis of the section, 30 those of the rectangular section guide and a circular aperture at the other end having a diameter corresponding to that of the circular waveguide, the two apertures having their edges contained in parallel planes and having their centre points located on the axis of the section, 35 a first passage bounded by two opposed broader faces and two opposed narrower faces and extending towards the circular aperture, said passage being of the same shape and cross-sectional area as said rectangular aperture and a second passage extending towards the rectangular aperture from the circular aperture in axial alignment with said first passage and having a first part of its wall lying to one side of a plane containing the aligned axes of said passages and normal to the broader faces of said first 40 passage arranged to constitute part of the surface of a frustum of a cone and a second part of its wall lying to the other side of said plane arranged to constitute part of the surface of a frustum of a similar cone each of said frustums having a larger end the diameter of which is substantially equal to that of the circular aperture and a smaller end of a diameter substantially equal to the smaller dimension of the rectangular aperture, each wall bounding said first passage to said one side of said plane meeting said first part of the wall of said second passage along a curved line contained in the plane of the respective wall of said first passage, and each wall bounding said first passage to said other side of said plane meeting said second part of the wall of said second passage along a curved line contained in the plane of the respective wall of said first passage.
